UNITED STATES PATENT OFFICE.

ARTHUR TREVOR DAWSON AND GEORGE THOMAS BUCKHAM, OF LONDON, ENGLAND, ASSIGNEES TO THE VICKERS, SONS & MAXIM, LIMITED, OF SHEFFIELD, ENGLAND.

CONCEALED FORT FOR ARTILLERY.

SPECIFICATION forming part of Letters Patent No. 614,702, dated November 22, 1898.

Application filed May 16, 1898. Serial No. 680,835. (No model.)

To all whom it may concern:

Be it known that we, ARTHUR TREVOR DAWSON and GEORGE THOMAS BUCKHAM, citizens of England, residing at 28 Victoria street, Westminster, in the city of London, England, have invented a certain new and useful Concealed Fort for Artillery, (for which we have made application for a patent in Great Britain, No. 5,357, dated March 4, 1898,) of which the following is a specification.

Our invention relates to the mounting of a breech-loading gun in a fort in such a manner that the whole of the mounting and the vital parts of the gun, as well as the gunners and ammunition, are completely protected and concealed and that the gun can be easily and quickly withdrawn inside the fort when it is not in use.

We shall describe a fort according to our invention, referring to the accompanying drawings.

Figure 1 is a vertical section, and Fig. 2 is a sectional plan.

The fort generally is constructed of masonry A, on which is an armor-plate roof B, preferably convex. In front there is an embrasure the bottom C and sides D of which are preferably of thick chilled metal strong enough to protect the lower part of the gun-mounting and the masonry. Above the embrasure a curved armor-plate E, which forms the front, is secured inside to the sides D of the embrasure. There are also secured to the sides of the embrasure two wing armor-plates F, which project obliquely inward, so as to approach nearly to the center of the gun-mounting G, which is fixed close up to the front of the fort and guarded by a circular-fronted armor-shield. Thus the construction of the front of the fort and the armor-wing-plates F, the position of the mounting G, and its circular shield form an arrangement similar to the casemate-mounting of guns on board ship.

The whole of the fort except the embrasure 45 may be covered up and concealed with earth-work H.

The gun when not in use can be withdrawn completely inside the fort on a trolley K, which may run on rails. This trolley is run 50 under the breech end of the gun and carries it and the cradle, while guide-rollers on the mounting G support the chase of the gun as the gun is run back. To allow for the gun and cradle being quickly withdrawn, as described, the trunnion-bearings are made with gaps which can be turned to the rear to allow the trunnions to be withdrawn, as described in an application.

Projectiles may be stored around the inside 60 of the fort and ammunition in a room L, constructed at the rear of the fort under the earthwork.

The fort may be made of sufficient width to accommodate several guns, each shielded 65 and situated behind an embrasure protected as described.

We claim—

A fort having sides and rear constructed of masonry and an armor-plate roof having 70 in its front an embrasure with bottom and sides made of chilled metal, its upper part closed by a curved armor-plate and on each side an oblique wing-plate substantially as described.

In testimony whereof we have hereunto set our hands in presence of two subscribing witnesses.

ARTHUR TREVOR DAWSON.
GEORGE THOMAS BUCKHAM.
